Filed Sept. 26, 1960, Ser. No. 62,263

Term of patent 14 years

(Cl. D52—7)

FIG. 1.

FIG. 2.

FIG. 4.

FIG. 3.

FIG. 5.

FIGURE 1 is a view in front elevation of a wall thermostat embodying my new design.

FIGURE 2 is a view in side elevation of the same.

FIGURE 3 is a top plan view of the same.

FIGURE 4 is a view in elevation of the rear side of the same.

FIGURE 5 is a fragmentary perspective view illustrative of the grill and the window of the wall thermostat shown in FIGURE 1.

The undisclosed side of the thermostat is substantially the same in appearance as the side shown.

The dominant features of the design reside in the portions shown in full lines.

I claim:

The ornamental design for a wall thermostat, as shown and described.
